UNITED STATES PATENT OFFICE.

JULIUS STROHEIM, OF NEW YORK, N. Y., ASSIGNOR TO SCHOFIELD, MASON & CO., OF PHILADELPHIA, PENNSYLVANIA.

DESIGN FOR A RUG.

SPECIFICATION forming part of Design No. 18,996, dated April 2, 1889.

Application filed February 16, 1889. Serial No. 300,201. Term of patent 3½ years.

To all whom it may concern:

Be it known that I, JULIUS STROHEIM, a citizen of the United States, residing in the city of New York, county of New York, State 5 of New York, have invented or produced a new and original Design for a Pattern to be Inwrought into Wilton Rugs and other Carpeting; and I do hereby declare that the photographic illustration accompanying this specification gives and conveys to any one skilled 10 in the art of carpet-weaving a defined and thorough description of the nature of my invention, that is sufficient to enable any one so skilled to use my invention.

What I claim as my invention, and desire 15 to secure by Letters Patent, is—

The design for Wilton rugs, as shown in the photographic illustration accompanying this specification.

JULIUS STROHEIM.
